CLAIM

The ornamental design for a vaporizer device, as shown and described.

DESCRIPTION

The patent or application file contains at least one drawing executed in color. Copies of this patent or patent application with color drawing(s) will be provided by the Office upon request and payment of the necessary fee.

FIG. 1 shows a front plan photograph of a first embodiment of a vaporizer device showing our design; a reference view thereof is shown on page 1 of the Appendix;

FIG. 2 shows a rear plan photograph thereof; a reference view thereof is shown on page 2 of the Appendix;

FIG. 3 shows a side plan photograph thereof; the other side plan photograph is substantially the same;

FIG. 4 shows a top perspective photograph thereof; a reference view thereof is shown on page 3 of the Appendix;

FIG. 5 shows a top plan photograph thereof;

FIG. 6 shows a bottom perspective photograph thereof; a reference view thereof is shown on page 4 of the Appendix; and

FIG. 7 shows a bottom plan photograph thereof.

FIG. 8 shows a bottom perspective view of a second embodiment of a vaporizer device showing our design;

FIG. 9 shows a top perspective view thereof;

FIG. 10 shows a front plan view thereof;

FIG. 11 shows a side plan view thereof; the opposite side plan view is substantially the same;

FIG. 12 shows a rear plan view thereof;

FIG. 13 shows a bottom plan view thereof; and

FIG. 14 shows a top plan view thereof.

FIG. 15 shows an exploded bottom perspective view of a third embodiment of a vaporizer device showing our design;

FIG. 16 shows an exploded top perspective view thereof;

FIG. 17 shows an exploded front plan view thereof;

FIG. 18 shows an exploded side plan view thereof; the opposite exploded side plan view is substantially the same;

FIG. 19 shows an exploded rear plan view thereof;

FIG. 20 shows a bottom plan view thereof; and,

FIG. 21 shows a top plan view thereof.

(Continued)

The broken lines show portions of the vaporizer device that form no part of the claimed design.
